UNITED STATES PATENT OFFICE.

PAUL G. SCHWARZ, OF INDIANAPOLIS, INDIANA.

FOLDING TOOTHRUSH.

1,302,269.

specification of Letters Patent. Patented Dec. 14, 1920.

Application filed May 3, 1920. Serial No. 378,585.

To all whom it may concern:

Be it known that I, PAUL G. SCHWARZ, a citizen of the United States, residing at Indianapolis, in the county of Marion and State of Indiana, have invented certain new and useful Improvements in Folding Tooth-brushes, of which the following is a specification.

My said invention consists in certain improvements in the details of construction and arrangement of parts of folding tooth brushes, whereby a brush of this type is provided wherein all the parts except the bristles are capable of indefinite use, and wherein new sets of bristles may be readily and cheaply substituted for old sets, and whereby a tooth brush is provided which is sanitary in its construction and convenient for use, all as will be hereinafter more fully described.

Referring to the accompanying drawings, which are made a part hereof and on which similar reference characters indicate similar parts:

Fig. 1 is a plan view looking at the tooth brush toward the top of the bristles and when the brush is open and ready for use,

Fig. 2 a longitudinal sectional view looking in the direction indicated by the arrows from the dotted line 2—2 in Fig. 1,

Fig. 3 a plan view of the brush folded,

Fig. 4 a perspective view of the handle portion of the brush separately,

Fig. 5 a plan view of the blank as formed, ready to make the handle, and

Fig. 6 a plan view of the blank as formed ready to make the bristle holders.

In said drawings the portions marked A represent the handle and B and C a brush holder formed in two parts each of which has a shank portion.

The handle A is cut out of sheet metal to the form shown in Fig. 5 and then formed by bending, by dies or in any manner preferred, along the points indicated by dotted lines in said figure to make a handle of the form shown in Fig. 4. The raised central portion 10 at the outer end is formed by bending over the rear part of the stamped blank and turning down the edges thereof, as indicated by the dotted lines in Fig. 5. The back of said handle is cut from a point 11 along lines near each side to a point 12, forming a spring back adapted to operate in substantially the same manner as the back spring in a pocket knife. The front bar 13 of

the frame is solid with the sides thereof, making a rigid construction at the front as well as at the rear. Near the front end in the sides are formed holes 30 in which the pivots 60 of the brush holder B—C are mounted.

Said brush holder B—C is connected by a pin 15 in the same manner as the two parts of a pair of shears, the pin being fixed in one part and having an elongated head that 65 is adapted to pass through a correspondingly shaped opening in the other part, but at right angles thereto when in normal position, as shown. Each of the forward ends of said parts are formed with sides 16, with 70 overturned top edges 31, ends 17 and in-turned flanges 18 at the rear ends forming box-like casings open on their adjacent sides for receiving the bases 19 holding the bristles. Said bases 19 with the bristles 75 mounted therein are formed of rubber or other suitable material and adapted to fit into the metal cases thus formed, being slid into position from the inner or adjacent sides and held in position by close contact 80 with each other when the brushes are in position for use. Back of the pin 15 the brush holder is formed with a shank portion and an upturned flange 20 in which is rigidly mounted an outwardly projecting pivot 21 85 adapted to engage with the hole 30 in the flange 14 of the handle. The ends of said shank portions are formed with ends 22, bent up at a slight angle from the outer edge toward the inner edge, as on dotted line 23, 90 Fig. 6, for a purpose to be presently described.

The parts B and C are also stamped out of metal and the edges turned to form the parts into the proper shape, as indicated by 95 dotted lines in Fig. 6.

In the construction the parts are so proportioned and adjusted that when the brush is opened for use the inner edges of the parts of holder B—C will first contact and as they 100 are brought to full opened position they will bear closely against each other, slightly springing at said ends so that their adjacent edges will bear closely and form a brush which as a whole will be for all practical 105 purposes unitary in its structure.

In operation the brush being open, as shown in Fig. 1, and it being desired to close the same the parts B and C are turned upwardly on the pivots 21. As they are turned 110 upwardly the spring back 25 of the handle yields under the pressure and when the parts

come to a position at right angles with the handle the ends 22 cause said spring back to hold said brush holder parts inclined apart so that the brush bases which are held 5 in holder B—C by friction may be removed and one of said bases placed edgewise in the opening in raised portion 10 and the other similarly on spring back 25. Continuing the turning of parts B and C the sides of 10 the handle receive the parts spreading them so that each will fit on the appropriate side of the central raised portion 10 of the handle and the ends 22 will snap into position, the flanges 20 into openings 33 between the edges 15 and the end of the spring back 25, thus locking the parts closely in position and holding the device closed. In opening the device the reverse operation is proceeded with, the inturned ends 26 at the front end of the 20 handle serving as cams to guide the parts B and C and close them tightly together, as before described.

By this means a very convenient structure is provided for the purpose and one 25 in which the brush parts can be readily interchanged, as desired, the handle and parts B and C being formed of any attractive design or material, as will be readily understood.

30 Having thus fully described my said invention, what I claim as new and desire to secure by Letters Patent, is:

1. A device of the class described comprising a handle formed with raised portions, a spring back on said handle, a folding brush holder comprising two relatively movable parts, said raised portions being adapted to receive said brush holder, brushes carried by said holder, said holder 35 being mounted on pivots in said handle the ends of the same bearing against said spring back and adapted to be retained in position thereby.

2. A device of the kind described, comprising a handle formed with a back and with side flanges, the forward ends of said flanges being offset inwardly, and the back being provided at the forward end with a spring, a brush holder in two parts hinged 50 together and having shanks provided with pivots adapted to engage slots in the side flanges adjacent to the front end, said shanks provided with flat surfaces adapted to bear against said spring to hold said holder in position.

3. A device of the kind described, comprising a handle formed with a back and with side flanges, the forward ends of said flanges being offset inwardly, and the back 55 being provided at the forward end with a spring, a brush holder in two parts hinged together and having shanks provided with pivots adapted to engage slots in the side flanges adjacent to the front end, said shanks provided with flat surfaces adapted

to bear against said spring to hold said holder in position, said flanges having inwardly extending portions forming guiding cam surfaces.

4. A device of the kind described comprising a handle formed with a back and with side flanges, the forward ends of said flanges being offset inwardly, and the back being provided at the forward end with a spring, a brush holder in two parts hinged together 70 and having shanks provided with pivots adapted to engage slots in the side flanges adjacent to the front end, said shanks provided with flat surfaces adapted to bear against said spring to hold said holder in 75 position, a receptacle in each of said brush holder parts open on the face adjacent to the other, overhanging flanges on the outer edges thereof, and bristle holding bases adapted to be inserted in said receptacle. 80

5. A device of the kind described comprising a handle, a folding brush holder the parts of which are hinged together and each hinged to said handle, and removable bristle carrying bases mounted in said brush 90 parts, substantially as set forth.

6. A device of the kind described comprising a handle, a brush holder in two parts which are hinged together and each pivoted to said handle, said brush holder 95 parts being formed with overhanging flanges except at their adjacent sides to form box-like casings for receiving bristle holding bases, and removable bristle holding bases mounted in said box-like casings, substantially 100 as set forth.

7. A device of the class described, comprising a handle having compartments therein, a brush holder pivoted thereto, spring means adapted to retain the brush 105 holder in a plurality of positions, bristle holding bases carried by said holder, and means for removably securing said bases to the holder, said bases fitting in the compartments of the handle when removed from 110 the holder.

8. A device of the class described, a handle, a spring back adjacent one end of the handle, a pair of crossed brush-holding members having one of their ends pivoted 115 to the handle, means for pivotally securing the brush holders together, and means on said holders for causing the brush-holding ends to move away from each other when the holder is moved to closed position. 120

9. A device of the class described, a handle, a spring back adjacent one end of the handle, a pair of crossed brush-holding members having one of their ends pivoted 125 to the handle, means for pivotally securing the brush holders together, means on said holders for causing the brush-holding ends to move away from each other when the holder is moved to closed position, and means at the other end of the handle for 130

forcing the outer ends of the brush-holding members together when the holder is moved to open position.

10. In a device of the class described, a handle member having flanges thereon, a pair of brush-holding members having substantially scissors action, means for pivoting the inner ends of said brush-holding members between the flanges of the handle, and inclined members on the inner ends of said brush-holding members for separating the outer ends of the brush-holding members when the brush-holding members are moved to closed position.

11. In a device of the class described, a handle member having flanges thereon, a pair of brush-holding members having substantially scissors action, means for pivot-

ing the inner ends of said brush-holding members between the flanges of the handle, 20 inclined members on the inner ends of said brush-holding members when the brush-holding members are moved to closed position, and inturned ends on the handle for forcing the outer ends of the brush-hold- 25 ing members together when said members are moved to open position.

In witness whereof, I have hereunto set my hand and seal at Indianapolis, Indiana, this 20th day of April, A. D. nineteen hun- 30 dred and twenty.

PAUL G. SCHWARZ. [L.S.]
